(57) **CLAIM**

(21) Appl. No.: **29/504,757**

The ornamental design of a plastic insulator for connecting an electric fence wire to a corner fence post, as shown and described.

(22) Filed: **Oct. 9, 2014**

DESCRIPTION

(51) **LOC (10) Cl. 13-03**

FIG. 1 is a perspective view of a plastic insulator for connecting an electric fence wire to a corner fence post showing my new design;

(52) **U.S. Cl.**

FIG. 2 is a front view thereof, the opposite back view being a mirror image;

USPC **D13/129**

FIG. 3 is a side view thereof; the opposite side view being a mirror image;

(58) **Field of Classification Search**

FIG. 4 is a view of one end thereof;

USPC D13/129–133, 146, 147, 154, 156, 184,
D13/199; 174/158 F

FIG. 5 is an opposite end view thereof; and,

See application file for complete search history.

FIG. 6 is a section view thereof, taken on the line **6-6** of FIGS. 4 and 5.
